UNITED STATES PATENT OFFICE

2,677,201

SHOE OF THIN GAUGE SHEET METAL

George Albert Lyon, Detroit, Mich.

Application July 6, 1950, Serial No. 172,215

2 Claims. (Cl. 36—2.5)

1

This invention relates to shoes and more particularly to a metallic shoe that can be made from sheet metal stampings as well as to a new way of making a shoe.

An object of this invention is to provide for the making of a shoe from sheet metal stampings such, for example, as stampings from thin gauge resilient stainless steel.

Another object of this invention is to provide a metallic sheet metal shoe wherein the resilient characteristics of the metal are employed in the flexing of the shoe and in the gripping of the foot of the wearer.

Yet another object of this invention is to provide a sheet metal shoe which lends itself to very economical manufacture on a large production scale.

In accordance with the general features of this invention there is provided a shoe made of thin gauge resilient sheet metal comprising two substantially duplicate but oppositely opening shell-like halves joined together along a line lengthwise of the shoe and together forming the toe, back, heel and sole portions of the shoe.

Another feature of the invention relates to the forming of the toe portion of a shoe as aforesaid so as to include two opposite curved springy portions relatively flexible for fitting around and engaging the toes of the wearer.

Yet another feature of the invention relates to forming the heel portion of the aforesaid shoe hollow and providing an insert in the back portion of the shoe over the hole in the heel which constitutes an extension of the sole portion above the heel portion and closes off the hole in the heel.

Other objects and features of this invention will more fully appear from the following detailed description taken in connection with the accompanying drawing which illustrates several embodiments of the invention and in which:

Figure 1 is a plan view of my novel shoe;

Figure 2 is a side view of the shoe;

Figure 3 is a cross-sectional view taken on the line III—III of Figure 2 looking in the direction indicated by the arrows and showing the construction of the toe portion;

Figure 4 is a vertical sectional view taken on substantially the line IV—IV of Figure 1 looking upwardly;

Figure 5 is an exploded view showing two stampings or halves going to form my shoe prior to their being joined or welded together.

As shown on the drawings:

The reference character 10 designates generally 55 flexes as one walks with the same on. In addi-

2

a sheet metal shoe embodying the features of my invention. In Figure 5 I have shown how this shoe can be made from two substantially duplicate but oppositely facing sheet metal stampings 10a—10b, each of which has a straight edge 10c—10d which when engaged with the straight edge of the other half can be welded to join the two halves together. Any suitable welding equipment can be used for this purpose.

10 After the welding operation, the welded joint can be ground whereby the two halves appear to comprise a single unitary sheet metal fabrication.

Excellent results can be attained by stamping the right and left halves 10a—10b from resilient stainless steel sheet metal such as so-called 18-8 stainless steel. Preferably a very thin gauge of metal should be used such, for illustration, as a sheet of .018 inch thickness.

20 After the aforesaid joining of the shoe edges, suitable buffing and polishing apparatus can be employed for giving the sheet metal a very high luster if the same is desired. On the other hand, any suitable finishes, colored or otherwise, can also be imparted to this sheet metal fabrication.

25 Now referring to Figures 1—4, inclusive, it will be perceived that the shoe thus formed includes a toe portion 11, a back or quarter portion 12, a heel portion 13, and a sole portion 14. The toe portion 11 includes two opposite curved toe gripping portions 11a—11a between which is a keyhole shaped space 15 through which the toes of the wearer of the shoe are visible. In order to reinforce and ornament the entire upper edge 30 of the shoe, I curl or bead the edge at 16. This bead also serves the purpose of eliminating any sharp edge which would cut or injure the wearer.

35 Now since the heel portion 13 is formed hollow it, of course, becomes necessary to close off the heel at the top of this portion and this is enabled by providing a sheet metal insert 19 over the hole and which may be suitably joined or welded to the back portion 12 of the shoe.

40 If it is so desired, a conventional fabric or leather insole (not shown) could be inserted in the shoe on top of the sole portion 14. The use of such inner soles, of course, is well known and old in the shoe art generally and for that reason is not being shown or claimed herein.

45 By reason of the fact that both shell-like halves of my novel shoe are made of highly resilient very thin gauge sheet metal, the entire shoe can flex readily in the bending of the foot in much the same manner as a leather shoe now 50 flexes as one walks with the same on. In addi-

tion, the yieldable clip-like toe portions $11a$ snugly engage the toes of the wearer so as to assist in fitting the shoe to and holding it on the foot.

It will be understood that modifications and variations may be effected without departing from the scope of the novel concepts of the present invention.

I claim as my invention:

1. As an article of manufacture, a resilient, thin gauge, sheet metal shoe with a quarter portion, a heel portion, a sole portion, side portions and a toe portion, and having a main foot receiving opening, all of said portions being integral with each other and said side portions being continuous with said quarter and toe portions and each side portion having its top edge at said opening curving upwardly, rearwardly and forwardly to said quarter and toe portions respectively from a low point substantially at the forward portion of the instep region of said shoe, said main opening gradually curving at its front end into an opening in the top area of said toe portion and which latter opening is a longitudinally narrowed continuation of said main opening and which is extended to the sole portion where it widens at the front end of the sole portion substantially equally on each side of the longitudinal center line of the quarter, heel and sole portions, said shoe comprising opposite lateral halves formed to resiliently grip a foot and having a longitudinal line of junction at the median plane of the shoe with respect to which the sides of the toe portion are laterally resiliently yieldable at said opening in said toe portion, said longitudinal line of junction and said median plane being defined by the longitudinal center line of said quarter portion, said heel portion and said sole portion.

2. As an article of manufacture, a resilient, thin gauge, sheet metal shoe comprising two juxta-opposed halves joined along the longitudinal medial plane of the shoe, said halves coop-

erating to define the shoe toe, side, quarter and sole portions with the main shoe opening between said side and quarter portions above said sole portion, all of said portions being integral with each other and said side portions being continuous with said quarter and toe portions and each side portion having its top edge at said opening curving upwardly, rearwardly and forwardly to said quarter and toe portions respectively from a low point substantially at the forward portion of the instep region of said shoe, said main opening gradually curving at its front end into an opening in the top area of said toe portion and which latter opening is a longitudinally narrowed continuation of said main opening and which is extended to the sole portion where it widens at the front end of the sole portion substantially equally on each side of the longitudinal center line of the quarter, heel and sole portions, said toe portion opening dividing the toe portion into two lateral spaced wing-like sides resiliently movable apart over said sole portion and on opposite sides of said medial plane.
